UNITED STATES PATENT OFFICE

167,592

ORNAMENTED CANDY BOX

Michel Schwartz, New York, N. Y.

Application December 26, 1950, Serial No. 13,568

Term of patent 3½ years

(Cl. D58—14)

To all whom it may concern:

Be it known that I, Michel Schwartz, a citizen of the United States and resident of New York, in the county of New York, State of New York, have invented a new, original, and ornamental design for an Ornamented Candy Box, of which the following is a specification, reference being had to the accompanying drawing, forming a part thereof, and of which:

Fig. 1 is a front perspective view of an ornamented candy box, embodying my new design, and showing the cover removed from the body portion, and

Fig. 2 is a perspective view thereof showing the cover applied to the body portion.

The dominant feature of my design resides in the portions shown in full lines.

I claim:

The ornamental design for an ornamented candy box, as shown and described.

MICHEL SCHWARTZ.
